UNITED STATES PATENT OFFICE.

WILLIAM J. BRADLEY, OF TROY, NEW YORK, ASSIGNOR TO THE RAIL JOINT COMPANY, OF NEW YORK, N. Y., A CORPORATION OF NEW YORK.

ROLL CONSTRUCTION FOR ROLLING-MILLS.

1,244,464.

Specification of Letters Patent. Patented Oct. 30, 1917.

Original application filed March 20, 1915, Serial No. 15,790. Divided and this application filed July 10, 1915. Serial No. 39,157.

To all whom it may concern:

Be it known that I, WILLIAM J. BRADLEY, a citizen of the United States, residing at Troy, in the county of Rensselaer and State 5 of New York, have invented certain new and useful Improvements in Roll Constructions for Rolling-Mills, of which the following is a specification.

This invention relates to a novel roll construction for rolling mill operations, and having special utility as one of the units of a set of rolls for making a special design of 10 railway tie plate.

One of the leading objects of the invention 15 is to provide a sectional roll construction comprising a plurality of readily removable and replaceable units, thus reducing the expense of breakages to a minimum. A further object is to provide a sectional roll member having an adjustable characteristic 20 in the sense of being readily and inexpensively changed to vary the distance between the inside rail flange bearing shoulders of a railway tie plate.

25 With these and other objects in view which will be appreciated by those familiar with this art, the invention consists in the novel construction, combination and arrangement of parts hereinafter more fully described, illustrated, and claimed.

The essential features of the invention, involved in the sectional and adjustable feature of the improved roll member are susceptible of structural change within the 35 scope of the appended claim without departing from the spirit and purposes of the invention, but a preferred and practical embodiment thereof is shown in the accompanying drawings, in which:—

40 Figure 1 is an elevation of a set of rolls in a rolling mill embodying the improved sectional roll construction contemplated by the present invention.

Fig. 2 is an enlarged view of the improved 45 sectional roll member illustrating the same as forming the leader pass of the set of rolls for making the special design of tie plate referred to.

Fig. 3 is a detail view in perspective of 50 the special design of tie plate produced by the passes of the rolls illustrated in Fig. 1.

Similar reference characters designate corresponding parts throughout the several figures of the drawings.

Since the improved sectional roll member 55 possesses special utility as one of the units of a set of rolls for making a railway tie plate having certain structural characteristics, reference will first be made to the latter. A tie plate of this character is shown in Fig. 3 of the drawings, and includes a rectangular body plate 1 provided at the upper side thereof with a flat rail seating floor 2. At the opposite marginal edge portions of its floor, the body 1 has formed thereon the raised rib portions 3 and 4 respectively which are rounded on their upper surfaces, as at 5, and present at their inner edges the vertically disposed inside rail flange bearing shoulders 6. In addition thereto, the said 70 tie plate embodies other features of construction which are developed in the final pass of the rolls according to the process disclosed in my parent application Serial No. 15,790, filed March 20, 1915. 75

As already indicated, the improved sectional roll member, though susceptible of more general application, is specially adapted for use as one of the units of a set of rolls for making the special design of tie 80 plate described, and in the drawings the invention is shown as applied to a set of mill rolls generally designated by the reference letters A, B and C. These rolls provide a series of roll passes designated respectively 85 I, II, III, IV, and V in which are developed the tie plate or metal shape shown in Fig. 3 of the drawings. The passes I and II give to the bar its approximately primary form and size, and the pass V is the final 90 pass of the series and includes a roll formation which gives finished form to the various structural features of the tie plate. At the same time, the intermediate passes III and IV carry out a stage of the operation 95 which is rendered practical and effective by the novel construction of roll member constituting the present invention.

Referring now to the novel roll member claimed herein, it is to be noted that the same 100 provides for the final shaping and spacing of the inside flat bearing shoulders 6 of the tie plate, and this operation is accomplished in passes III and IV of the rolls. With respect to pass III, it will be 105 noted from Fig. 1 of the drawings that this pass is provided between roll members, one of which has a reducing collar 7 formed

with shallow peripheral grooves 8, and the other of which roll members includes rounded former rings 9, and intermediate reducing rings 10 and 11 which further develop the flat floor 2 of the bar blank, and one of which rings, designated by the reference number 11 may be termed a rib-gaging die-ring. This latter ring is readily removable and replaceable and is employed in varying sizes according to the required distance between the inside bearing shoulders 6, which distance is determined by the width of the rail base flange.

A further reduction and shaping to determine the distance between the inside shoulders 6 and the final working out of the projecting ribs from the base or under side of the blank are effected in pass IV. This pass is provided between roll members, one of which substantially consists of a plain reducing collar 12 which flattens the base. The other roll member of the pass IV comprises rounded marginal former rings 13, and intermediate reducing rings 14 and 15, the latter like the ring 11 being a rib-gaging die-ring and interchangeable with other sizes.

Thus, it will be seen that the sectional roll members for passes III and IV are substantially alike with respect to the adjustment feature of being adaptable to the required distance between the inside bearing shoulders 6 of the tie plate, and also with

respect to having all of their units readily removable and replaceable so as to reduce the expense of breakages to a minimum, entirely obviating the loss of an entire roll on account of only a portion of the roll being damaged.

From the foregoing, it is thought that the construction and many advantages of the improved roll construction described herein will be apparent without further description, and it will be understood that changes in the form, proportion, and minor details of construction may be resorted to within the scope of the appended claim.

I claim:

A roll for rolling shapes with spaced inside shoulders, the same including a pair of opposite marginal die-rings provided with shoulder-shaping die surfaces, and an intermediate ring interposed between the marginal rings and provided with a flat peripheral die surface and with flat shoulder-shaping die-edges, the latter overhanging the die surfaces of the marginal rings, the said intermediate ring being interchangeable with similar rings of different widths.

In testimony whereof I hereunto affix my signature in the presence of two witnesses.

WILLIAM J. BRADLEY.
